SHAVING IMPLEMENT

Joseph Muros, Cambridge, Mass., assignor to Gillette Safety Razor Company, Boston, Mass., a corporation of Delaware

Application March 24, 1938, Serial No. 197,893

5 Claims. (Cl. 30—43)

This invention relates to shaving implements of the type employing relatively movable shearing members and being designed for shaving without the use of lather. The invention consists in an improved construction for the stationary shearing member in those implements which include in their structure a thin resilient metal sheet which is perforated to present the stationary shearing edges.

10 In an endeavor to reduce the thickness of the stationary shearing member and so improve the efficiency and close-shaving characteristics of the implement, the attempt has been made to utilize a thin, perforated steel sheet which is not of itself sufficiently rigid to be self-sustaining but must be secured to a supporting frame in order that it may be given the curvature desired in the implement. This steel sheet is of necessity somewhat resilient since it must be tempered to give 15 it the required edge-holding properties. The attempt has been made heretofore to secure such a steel sheet to its supporting frame by soldering or braizing but this manner of attachment has not proved to be satisfactory or reliable in continued 20 use of the implement, since for one reason or another, the connecting medium deteriorates under the constant tendency of the steel sheet to straighten. The result is that after variable 25 periods of use the steel sheet becomes detached and if the user overlooks this condition he is likely seriously to damage himself by coming in contact with the oscillatory cutter which is ordinarily completely guarded by the perforated steel sheet.

30 An object of the present invention is to remedy the difficulties above discussed and to provide a construction in which a sheet steel shearing element of any desired thickness may be employed without danger of its becoming loosened or detached throughout the life of the implement. To this end, an important feature of the invention consists in a supporting frame having longitudinal members connected by curved or arched ribs, and a thin resilient shearing plate 35 conformed to the curvature of the arched ribs, together with means for positively clamping the edges of the plate to, or adjacent to, the longitudinal members of the frame.

40 While this is the broad conception of my invention it may be put into practice in various ways. For example, the inner face of the frame may be provided with projecting shoulders and the resilient plate may be conformed to the ribs and sprung at its edges into engagement with the shoulders, thereby becoming resiliently inter-

locked with the frame without the intervention of any connecting medium such as solder. Under such conditions, the resilient plate will maintain its position indefinitely since its tendency to straighten out has the effect only of intensifying the interlocking engagement between the plate and the frame. As an alternative construction, the longitudinal members of the frame may be slotted and the marginal edges of the resilient plate may be fitted into these slits and maintained therein by a swaging displacement of the metal of the frame, or as another alternative, a separate anchor or clip may be provided for interlocking mechanically with the frame and with the marginal edges of the sheet steel shearing member. As already intimated the exact mechanical construction employed is of secondary importance so long as an interlocking configuration is employed by which the edges of the steel sheet and the frame are mechanically connected while the body of the steel sheet conforms to the curvature of the frame.

45 These and other features of the invention will be best understood and appreciated from the following description of a preferred embodiment thereof, selected for purposes of illustration and shown in the accompanying drawing, in which:—

Fig. 1 is a fragmentary sectional view on an enlarged scale of a dry shaving implement embodying my invention in one satisfactory embodiment;

50 Fig. 2 is a view in perspective, on a scale reduced as compared to that of Fig. 1 but still enlarged in respect to the actual implement, showing the complete stationary shear member;

Fig. 3 is a fragmentary view in central cross-section of the member shown in Fig. 2 but on a greatly enlarged scale;

55 Fig. 4 is a sectional view on the scale of Fig. 1 illustrating in cross-section a stationary shear member of modified construction;

Figs. 5 and 6 are views in plan and elevation respectively of the member shown in Fig. 4 but on a somewhat reduced scale;

Fig. 7 is a view in cross-section illustrating a third construction of stationary member embodying my invention;

Fig. 8 is a view in perspective of one of the clip members used with the frame of Fig. 7; and

Fig. 9 is a fragmentary view in section showing a portion of Fig. 7 on a greatly enlarged scale.

The implement as shown in Fig. 1 comprises a casing 10 of "Bakelite" or any suitable mouldable material which serves as a handle for the implement and also as a housing for its driving

55

motor. The casing 10 is rectangular in cross-section and provided at its upper end with a skeleton supporting frame having semi-circular end ribs 11 connecting spaced elongated side members 12. An intermediate curved rib is also shown 5 as located midway between the ends of the frame and conforming in the curvature of its upper face to the curvature of the end ribs 11. Shaped to the ribs of the supporting frame and conforming to the transverse exterior curvature thereof is a 10 thin, resilient perforated steel sheet 13. The sheet is provided with a multiplicity of perforations 14, the edges of which form the stationary shearing edges of the implement and, as already seen, the perforated sheet is sufficiently hardened and tempered to insure that it has good edge-holding properties. By its temper it is rendered sufficiently resilient so that it tends normally to assume a flat condition and, therefore, it has to be 15 permanently confined in order to maintain the desired transversely curved condition. In addition to the shearing perforations the sheet 13 has a row of larger perforations along each of its longitudinal edges.

As herein shown the sheet steel 13 is secured 20 to the supporting frame by having its longitudinal marginal edges bent inwardly and fitted into a pair of longitudinal slits formed in the members 12 of the supporting frame. After the steel sheet has been thus positioned the metal of the frame 25 is swaged inwardly in a series of spots 16. Thus the marginal edges of the steel sheet are mechanically interlocked to its supporting frame and are permanently retained in position without reliance upon a connecting medium of any kind.

The assembled frame and sheet 13 form a rigid 30 self-sustaining unit which may be handled conveniently and attached to or detached from the casing 10 of the implement. To this end the opposite side members of the supporting frame are provided with notches 17 for the reception of 35 movable clamping arms 18 carried by the casing 10.

A portion of the motor 20 of the implement is shown in Fig. 1 as is also the movable shearing 40 member of the implement which comprises a flat blade 25 shaped at its edge to clear the intermediate rib of the supporting arm. The blade 25 is loosely held in a bar 23 which is provided at opposite ends with trunnions 24 and journaled 45 in transverse arms 26 which form part of the casing. The bar 23 is provided with a pair of downwardly extending longitudinal plates 22 spaced to receive between them a cylindrical eccentric member 21 projecting from the end of 50 the rotor of the motor. When the motor is energized the carrier bar 23 is rocked back and forth and the blade 25 is swept transversely across the 55 arcuate portion of the stationary shearing member 13. It will be understood that the implement is moved across the face of the user and that those hairs which enter the aperture 14 are sheared by the cooperating shearing action of the 60 movable blade 25 with the stationary shearing member 13.

In the embodiment of the invention shown in 65 Figs. 4, 5 and 6 the supporting frame is of skeleton construction and comprises elongated side members 30 connected by a pair of semi-circular end ribs 31 and an intermediate semi-circular rib 32. The end ribs 31 are of the full thickness 70 required to give strength to the frame while the intermediate rib is reduced in thickness and serves principally as a guide. In this instance the flexible shearing member is conformed to the 75

inner surface of the ribs 31 and 32 instead of their outer surface as in the embodiment of the invention already described. To this end, the inner arcuate surfaces of the three ribs are brought into a single cylindrical surface and each of the longitudinal members 30 is provided with an inwardly projecting rib 33 forming a reentrant longitudinal shoulder extending for the full length of the frame at opposite sides thereof.

The shearing member comprises a thin flexible sheet 34 rectangular in shape and provided with a multiplicity of small perforations arranged in rows in two substantially rectangular panels and having also a row of larger perforations spaced within its longitudinal marginal edges. The sheet 34 is of such width that it may be forced into conformity with the inner curved faces of the ribs 31 and 32 and snapped into place about the ribs 33 so that it is maintained by its resiliency within the supporting frame and forms therewith a self-sustaining unit. If desired, the longitudinal edges of the sheet 34 may be notched to receive a tongue or projection upon one or both of the ribs 33 thereby locking the sheet against longitudinal displacement. In this construction there is no 10 tendency for the sheet to disengage itself from the supporting frame since its resilient tendency to straighten causes it to engage the inner cylindrical surface of the frame. It may, however, be 15 disengaged from the frame by having one of its 20 edges sprung over the rib 33 and thus replacement is facilitated when the shearing edges of the perforations have become dulled by use. The thickness of the intermediate rib 32 is reduced so 25 that it constitutes no substantial obstruction 30 when the implement is moved across the face of the user.

In the embodiment of the implement shown in Figs. 7, 8 and 9 the supporting frame comprises longitudinal side members 40 connected by semi-circular transverse ribs 41. The outer surfaces of the ribs 41 lie in a single cylindrical surface and impart their shape to the flexible shearing member when the latter is conformed to them. This member comprises a thin flexible sheet 42, 40 substantially rectangular in shape and perforated in accordance with the pattern similar to that shown in Fig. 5. It is conformed to the supporting frame with its longitudinal marginal edges 45 registering with the members 40 of the frame. It is mechanically interlocked with these members by means of elongated clips 43 formed of flexible sheet metal and shaped to embrace the frame members 40. One edge of the clip is provided with inturned teeth 44 and when the clip has been 50 positioned upon the members 40 of the frame with the flexible sheet 42 overlying the members 40 the walls of the clip 43 are bent so that the teeth 44 extend inwardly through the marginal apertures of the plate. In Fig. 7 the clip at the right-hand 55 side of the supporting frame is shown as positioned but not closed into interlocking engagement while the clip at the left side of the frame is shown as bent into its clamping position with the teeth 44 engaging the upper surface of the 60 frame member 40. Preferably and as herein shown the inner wall of the clip is permanently secured, as by welding, to the frame and in completing the device it is only necessary to position the sheet 42 and bend inwardly the outer wall of 65 the clip. The thin sheet 42 is thus securely held in shaving position but it may be detached for replacement by springing the outer wall of the clip sufficiently to disengage the marginal perforations 70 of the clip. It will be understood that the unit 75

shown in Figs. 4-6 and the unit shown in Figs. 7-9 are intended for use in an implement of the character illustrated in Fig. 1.

Having thus disclosed my invention and described a preferred embodiment thereof for purposes of illustration but not by way of limitation, I claim as new and desire to secure by Letters Patent:

1. A shaving implement comprising a supporting frame having longitudinal members connected by curved ribs, a thin resilient shearing plate conformed to the curvature of said ribs and extending at its edges into proximity to the longitudinal members of the frame, means for positively clamping the plate to said longitudinal members, and a cooperating movable shearing member.

2. A shaving implement comprising a supporting frame having longitudinal members connected by arched ribs, a thin resilient shearing plate of rectangular shape conformed to the curvature of said ribs and interlocked at its edges with the longitudinal members of the frame, and a cooperating movable shearing member.

3. A shaving implement comprising a supporting frame having longitudinal members connected

by arched ribs and having parallel longitudinal shoulders in opposite sides of its internal surface, a thin resilient shearing plate yieldingly conformed to the curvature of said ribs and held in place thereagainst by engagement at its edges with said longitudinal shoulders, and a cooperating movable shearing member.

4. A shaving implement comprising a supporting frame having longitudinal side members connected by curved ribs and provided with a shoulder in the inner face of each side member, a thin resilient apertured plate yieldingly conformed to the inner face of said ribs and sprung at its edges into the shoulders of the side members, and means for holding said plate against longitudinal shifting with respect to the frame and a cooperating movable cutter.

5. A shaving implement comprising a skeleton supporting frame having an inner transversely curved surface and inwardly projecting shoulders at its opposite sides, and a thin resilient shearing plate interlocked with said shoulders and pressed by its own resiliency into conformity to the curved surface of said frame.
